STIFFENING OF DOUBLE COLLARS

Robert Hönigsberg, Vienna, Austria

Application February 7, 1935, Serial No. 5,459
In Germany February 9, 1934

3 Claims. (Cl. 2—132)

This invention relates to collars of soft or semi-stiff material, with a stiffener member, which is constructed upon a carrier, usually a bundle strip.

5 In pressing or ironing the collar, an undesirable glossy strip is liable to be produced by this connecting strip on the front of the upper collar. The object of the present invention is to obviate this disadvantage by locating the oblique stiffening member in a guide, which is formed on the under collar by notches or cuts or as a loop. An abutment of its own for the end of the stiffening member located in the bend or arch at the top of the collar is not necessary, since the head of 10 the stiffening member, which is preferably provided with a cross piece, either bears in the arch of the collar itself, or else the loop itself becomes the abutment. The loop is preferably made from a pocket embracing the cross piece, so that it is bounded on its upper edge by the arch of the collar and on the other edge by the pocket. In 15 this manner the exact position of the stiffening member is determined.

The lower end of the stiffening member is supported in a packet which is formed from the wall of the upper collar, the edges of the marginal hems, and a flap applied to the latter.

The invention is illustrated by way of example in the accompanying drawing, in which

30 Figure 1 shows the front portion of a double collar, with a guide for the stiffening member made by means of slits in the under collar;

Figure 2 shows the same form of construction with the under collar turned up;

35 Figure 3 shows the front portion of a double collar with a loop provided on the under collar.

Figure 4 shows the same with the under collar turned up, and

Figure 5 shows the front portion of a double 40 collar in which the cross piece of the stiffening member is inserted in slots in the under collar at right angles to the arch of the collar.

This new collar stiffening operates in the following manner:

45 In stiffening the tips of the upper collar 1, the stiffening member 6 is well supported and also well held in position without these holding devices impairing the manufacture or the appearance of the collar. In Figures 1 and 2 the small 50 rod-shaped stiffener 6 is drawn through two slots 3 and 4 arranged in the material of the under collar 2, is supported, when the collar is turned

down, against the arch 7, and is inserted in a pocket 13 located at the tip of the collar. The slots in the under collar prevent longitudinal movement, and likewise lateral movement. When the collar is being pressed or ironed, these slots 5 do not in any way form a hindrance.

In the construction illustrated in Figures 3 and 4, the stiffening member 6 is passed through a pocket-like loop 18 until its cross piece 17 is completely introduced. When the lower collar is 10 turned down it is held fast by the arch of the collar and the loop, and therefore at the same time gives the stiffening member its direction, the lower end of the said stiffener being received by a pocket 13, as in the form of construction 15 illustrated in Figures 1 and 2.

In the construction according to Figure 5, the cross piece 17a, 17b is held by a loop, which is formed in the under collar by two slots or cuts 21, 22 in the lower collar 2 at right angles to the 20 collar arch 7. Here again the position of the stiffening member on the upper collar 16 is ensured. The pocket 15 arranged at the point of the collar is preferably formed by constituting it of the collar wall 16, the edges 8 and 9 of the 25 marginal hems 10 and 11, and flap 15 provided on the latter. The seams are indicated at 12 and 14.

What I claim is:

1. A folded collar including a neckband and an 30 outer fold connected with said band and having front tips, a stiffening member, a support for one end of said stiffening member at each tip of the outer fold, each stiffening member extending obliquely to the tip of the collar, a cross piece carried by the terminal of the stiffening member disposed adjacent the collar fold and extending obliquely to the stiffening member with the acute angle at the front, a support for said cross piece locking the latter against accidental withdrawal, 40 the portion of said stiffening member lying between said supports being freely disposed.

2. A folded collar as claimed in claim 1 characterized in that the second mentioned support includes a pocket-like member secured to the 45 neckband of the collar.

3. A folded collar as claimed in claim 1 characterized in that the second mentioned support is constituted by slits formed in said neckband and receiving the opposite ends of the cross member. 50

ROBERT HÖNIGSBERG.
